UNITED STATES PATENT OFFICE.

JACOB W. PORCHER, OF PORT WASHINGTON, OHIO.

HORSESHOE.

SPECIFICATION forming part of Letters Patent No. 761,904, dated June 7, 1904.

Application filed September 30, 1903. Serial No. 175,214. (No model.)

To all whom it may concern:

Be it known that I, JACOB W. PORCHER, a citizen of the United States, residing at Port Washington, in the county of Tuscarawas and 5 State of Ohio, have invented certain new and useful Improvements in Horseshoes, of which the following is a specification.

This invention provides improvements in horseshoes of the composite type embodying 10 a shoe consisting of hoof and tread sections. The sections of the shoe are of peculiar formation, so as to be movably secured together to permit of ready detachment of the tread-section from the hoof-section.

15 For a full description of the invention and the merits thereof and also to acquire a knowledge of the details of construction of the means for effecting the result reference is to be had to the following description and drawings 20 hereto attached.

While the essential and characteristic features of the invention are susceptible of modification, still the preferred embodiment of the invention is illustrated in the accompanying 25 drawings, in which—

Figure 1 is a perspective view of the horse-shoe, showing the sections locked together. Fig. 2 is a sectional view through the toe portions of the sections of the shoe when assembled in co-operative relation, the sections being 30 taken longitudinally of the V-shaped clamping member by which the sections are locked together. Fig. 3 is a transverse sectional view through the heel portions of the 35 shoe. Fig. 4 is a detail perspective view of the V-shaped clamping member used for locking the sections of the shoe together.

Corresponding and like parts are referred 40 to in the following description and indicated in all the views of the drawings by the same reference characters.

The hoof-section 1 of the shoe is of a form somewhat similar to the ordinary shoe commonly used, with the exception that the same 45 is not provided with calk devices, being also made lighter than the shoe commonly employed. The section 1 is provided with a plurality of openings 2, by which the same is secured to the hoof of the animal, as will be 50 readily seen. The heel portions of the section

1 are beveled upon the inner edges thereof, as shown at 3, for reasons which will more fully appear as the description proceeds. The embodiment of the invention as shown in the drawings illustrates the shoe having the tread-section of a construction to provide a cushion-shoe more especially adapted for use in the summer season. The tread-section, as shown, comprises a metal shoe-section molded in rubber 4, the metal portion being designated 5. 55 The rubber portion 4 of the tread-section is the portion of the same coming into direct contact with the ground and upon which the wear is received. I contemplate, however, the substitution of calks for the rubber portion of the tread-section should this be desirable. Calks upon the tread-section are valuable in the wintry season, when roads are usually in icy condition, endangering slipping of the animal, so that the provision of the 60 calk means aforesaid would avoid any likelihood of injury which might be caused by slipping. To secure the tread-section to the hoof-section, the former is provided adjacent the heel portions thereof and upon the outer faces 65 of the said heel-sections with lugs 6, which are adapted by a slideable movement of the tread-section to engage the beveled portions 3 of the heel portions of the hoof-section. To hold the lugs 6 in engagement with the heel 70 portions of the hoof 1, a V-shaped clamping member 7 is provided, the respective arms of the said member being adapted to engage the toe portions of the parts 1 and 5, upon opposite sides thereof, to thereby lock the said sections together at this point. To prevent displacement of the clamping member 7, pindle-lugs 8 are projected inwardly from the toe 75 portion of the tread-section, and a pin 9, passing through an opening 10 in the member 7 80 and the openings in the pindle-lugs, holds the member 7 in the engaging relation above described. A recess 11 upon the upper side of the hoof-section 1, adjacent the toe portions 85 thereof, receives the engaging portion of one of the arms of the V-shaped clamping member when the latter is disposed in a position so as to lock the tread and hoof sections together. The recess 11 when engaged by the 90 clamping member 7 prevents lateral play or 95 100

movement of the tread-section of the shoe, which is essential in order to prevent disengagement of the lugs 6 from heel portions of the hoof-section 1. The lugs 6 are oppositely 5 inclined, so as to more effectually engage with the beveled portions 3 of the hoof-section 1. To remove the detachable tread-section, it is only necessary to displace the pin 9, and thereby admit of removal of the clamping member 10 7, when by a slidable movement of the tread-section the latter may be separated from the hoof-section.

Having thus described the invention, what is claimed as new is—

15 In a composite horseshoe, the combination with a hoof-section, a tread-section, oppositely-inclined lugs projected from the outer faces of the heel portions of the tread-sections and adapted to engage the beveled inner edges of 20 the heel portions of the hoof-section, the hoof-

section being provided upon the toe portion thereof with a recess, pintle-lugs projected inwardly from the tread-section adjacent the toe portion thereof, and a V-shaped clamping member removably secured between the aforesaid pintle-lugs having its arms adapted to engage the sections of the shoe upon opposite sides to lock the same together at the toe portion and to prevent disengagement of the lugs of the tread-section from the hoof-section, one 25 30 of the arms of the V-shaped member aforesaid being adapted to enter the recess upon the toe portion of the hoof-section.

In testimony whereof I affix my signature in presence of two witnesses.

JACOB W. PORCHER. [L. S.]
